TRIMMING.

No. 18,953.

Patented Mar. 12, 1889.

UNITED STATES PATENT OFFICE.

JOHANN C. F. EDELMANN AND ALPHONSE H. KURSHEEDT, OF NEW YORK,
N. Y., ASSIGNEES TO THE KURSHEEDT MANUFACTURING COMPANY, OF
SAME PLACE.

DESIGN FOR TRIMMING.

SPECIFICATION forming part of Design No. 18,953, dated March 12, 1889.

Application filed January 21, 1889. Serial No. 297,103. Term of patent 7 years.

To all whom it may concern:

Be it known that we, JOHANN C. F. EDELMANN and ALPHONSE H. KURSHEEDT, both of the city, county, and State of New York, have 5 invented and produced a new and original Design for Dress-Trimming, of which the following is a specification, reference being had to the accompanying photograph, forming part hereof, which is a face view of our newly-designed dress-trimming.

The leading features of our design consist, first, of a lyre-like figure embracing a rosette and sprays extending from the rosette; second, of a border having bars, V-shaped figures, 15 and a stem, and, third, of the lyre-shaped figures, rosettes, sprays, bars, V-shaped figures, and a stem.

In the accompanying photograph, A represents fanciful lyre-like figures, each embracing a rosette, a. b are sprays extending from

each rosette a. The border B has two bars, e, and V-shaped figures f between said bars, on a central stem, g.

We claim—

1. The design for a dress-trimming, consisting of the lyre-shaped figures A, rosettes a, and sprays b, substantially as shown. 25

2. The design for a dress-trimming, consisting of the border B, having bars e e, V-shaped figures f, and stem g, substantially as shown. 30

3. The design for a dress-trimming consisting of the lyre-shaped figures A, rosettes a, sprays b, bars e e, V-shaped figures f, and stem g, substantially as shown. 35
